UNITED STATES PATENT OFFICE.

JAMES H. OKELL, OF LOS ANGELES, CALIFORNIA.

CORE-DRILL.

1,193,468.

Specification of Letters Patent.

Patented Aug. 1, 1916.

Application filed September 8, 1915. Serial No. 49,514.

To all whom it may concern:

Be it known that I, JAMES H. OKELL, a citizen of the United States, residing at Los Angeles, in the county of Los Angeles and 5 State of California, have invented new and useful Improvements in Core-Drills, of which the following is a specification.

My invention relates to that class of core drills which is used for obtaining cores out 10 of the ground being drilled or examined, and the object thereof is to provide a drill of simple and effective construction which can be operated at a minimum cost, and which is adapted for drilling through hard 15 substances.

Heretofore drills have been used in which diamonds have been disposed in the cutting edges thereof, thereby making the drills costly. Sometimes when in operation, the 20 drill would come to a crevice, and the diamonds loosened through the continuous use would drop out and be lost, and their places must be refilled with other diamonds, thereby making the operation exceedingly 25 costly.

I am also aware that drills have been constructed in which vertical and annular slots were formed in the lower or drilling end, and the edges were chamfered, flared and 30 parallel. With such drill, chilled shot and other abrading substances were used, but in drills of such construction the shot or other abrading substance is liable to become wedged between the body of the drill and 35 core, thereby expanding the bottom of the drill, causing it to cut a larger hole than is necessary, and also causing the bottom of the drill to become weakened, and distorted in shape so that other than a true circle is 40 formed. This causes the cores to break into fragments, greatly retarding the work and drill, thereby making it expensive, due to the loss of time consumed in doing this.

In my improved tubular drill, I avoid 45 these objections by not having any slot in the drill whatsoever, thereby not weakening the same. Such construction enables the drill to retain both its strength and original 50 circular design, which, I find, is of great importance and value in formations that are naturally broken and shattered and in which the loosened particles of the same constantly coming in contact with any slot during the 55 rotation of the drill while in operation, have a tendency to wedge said drill and increase the danger of twisting off the drill rods.

In core drills it is necessary to use a continuous flow of water for the removal of the cuttings or debris which are created during drilling of a hole. A variable quantity and 60 volume of water is required and I have found it advisable not to use any slot or opening of any type at the bottom of such drill, as all shot or abrasives used in drilling must necessarily lay upon the bottom of the 65 hole to become effective. In many conditions of formations, it is found necessary to use large volumes of water which I find when passed through any slot or similar opening in the bottom of the drill washes 70 and carries away the abrasive from the bottom of the hole with the drillings or debris, thereby causing great waste of abrasive and destroying the cutting efficiency.

In my improved drill I overcome these 75 objections by using perforations which can be plugged, the object of which is that the plugs can be removed in number sufficient when desired, to allow a larger volume of water to be used when found necessary. 80

An embodiment of my invention is illustrated in the accompanying drawing, in which:

Figure 1 is a side elevation partly in section. Fig. 2 is a fragmentary elevation 85 showing the positions of the perforations. Fig. 3 is a section as seen on the line 3—3 of Fig. 3.

The drill head comprises a tubular member 4 preferably having a flat lower end 5. 90 Disposed in the cylindrical wall of the tubular member 4 are perforations 6 which may be closed with plugs 7. The plugs 7 are of such character that they may be inserted in perforations 6 by means of a hammer and 95 removed with the aid of a punch. The perforations are preferably arranged in substantially helical form, as will be particularly noted from Fig. 2. The upper end of the drill tube is internally threaded as indicated at 8 for engagement with the reducing or driving head 9. A hollow drill rod 10 is secured by means of threads to the reducing head.

11 indicates the material from which the 105 core is to be taken and 12 the core. Abrasive material indicated by 13 such as chilled shot are disposed in the hole and about the lower end of the drill head.

Rod 10 is rotated causing rotation of the 110 drill tube and cutting of the material to be cored. Water for cleaning out the drillings

and debris enters the drill head through the drill rod, passes downward and through the unplugged perforations, then upward along the side of the drill tube carrying with it the drillings and debris.

The helical arrangement of the perforations is from left to right when the drill is intended to be rotated from right to left so that the openings allow water to pass through and engage with the drillings and the debris giving the same an additional upward movement, thereby reducing friction upon the sides of the drill tube and enabling the drill to give better cutting action. If the drill were rotated in a direction reverse to the helix the drillings and debris would be forced downward and packed around the sides of the drill, preventing it from coming in contact with the abrasive material and thereby defeating the purpose for which it is used.

By the use of plugs in the perforations, plugs may be removed at any point desired, thereby enabling the operator to control the volume of water and keep the same from coming in contact with the bottom of the bore and such abrasives as may be used at that point.

Another advantage that is gained by this type of perforation is that the water in its exit through the perforations extending

over a larger axial length of said drill has a better clearing action and removes the drillings with more efficiency, thereby reducing the possibility of clogging and wedging. In formations that disintegrate rapidly under the action of water, a larger volume of debris over that of actual drillings must be removed and this requires an increased volume of water. The number and position of plugs removed are selected with reference to the particular formation of the material drilled.

What I claim is:

1. The combination of a tubular drill, comprising a barrel provided in its cylindrical wall with perforations adapted to be plugged, said perforations distributed over the cylindrical surface of said barrel for the outflow of water, and loose abrasives disposed at the cutting edge of said drill.

2. The combination of a tubular drill, comprising a barrel provided in its cylindrical wall with perforations adapted to be plugged, said perforations disposed over the length of the barrel in helical form, and loose abrasives disposed at the cutting edge of said drill.

In witness that I claim the foregoing I have hereunto subscribed my name this 26th day of August, 1915.

JAMES H. OKELL.
